CYLINDER RELIEF COCK

Daniel Allcott Kelly, Milwaukee, Wis., assignor to
 Prime Manufacturing Company, Milwaukee,
 Wis.

Application March 22, 1945, Serial No. 584,081

2 Claims. (Cl. 121—134)

1

This invention appertains to valves and more particularly to a cylinder drain cock for steam engines.

One of the primary objects of my invention is to generally improve the operation and construction of automatic drain cocks for the cylinders of locomotives of the type embodying a valve for permitting the flow of water through the cock and movable on its seat to a closed position by steam pressure and a second valve for relieving the cylinder and cock of any high pressure which might develop from water of condensation collecting in the cylinder during the running of the engine.

Another salient object of my invention is the provision of novel means for forming the casing of the cylinder cock for the reception of a removable strainer plug, whereby to effectively prevent the movement of debris to the valves and seats of the cock.

A further important object of my invention is the provision of a vertically disposed strainer plug arranged directly below the inlet connection for the cylinder and between the drain valve and the relief valve, so that the strainer plug will effectively function to protect both valves and seats from cylinder debris.

A still further object of my invention is the provision of novel means for mounting the drain valve and the relief valve in the cock casing, so that the valves can be easily fitted in the casing and quickly removed for repairs, inspections and the like.

With these and other objects in view, the invention consists in the novel construction, arrangement, and formation of parts, as will be hereinafter more specifically described, claimed, and illustrated in the accompanying drawing, in which drawing:

Figure 1 is a top plan view of my improved automatic cylinder drain cock, parts of the view being shown broken away and in section to illustrate structural detail.

Figure 2 is a longitudinal sectional view through the cock, taken on the line 2—2 of Figure 1, looking in the direction of the arrows.

Referring to the drawing in detail, wherein similar reference characters designate corresponding parts throughout the several views, the letter "C" generally indicates the improved automatic drain cock and the same includes the body or casing 5 which can be formed from any preferred or desired material. As is clearly shown in Figure 2, this casing 5 is of a substantially cruciform in

vertical section, for a purpose which will later appear.

This casing 5 is provided with a vertical bore or passageway 6, and the upper end of said bore or passageway is threaded as at 7 for connection with a drain pipe leading from the opposite ends of an engine cylinder. The lower end of the bore or passageway 6 is internally threaded as at 8 for the reception of a removable strainer plug 9 which will be later described in detail.

The body or casing 5 is provided with a horizontal passageway 10 which bisects the passageway 6 and one end of this passage removably receives companion valve seats 11 and 12 for a drain valve 13, and the other end of the passageway receives a valve seat 14 for the reception of a relief valve 15.

Referring to the companion valve seats 11 and 12, it will be noted that the same are arranged in facing relation relative to one another and form a cup or cage for the ball valve 13. The ball valve 13 rests normally by gravity between the valve seats in an open position.

The passageway 10 is counter-bored for the reception of these seats as at 16 and a gasket 17 is fitted on the shoulder formed by said counter-bore. The inner valve seat 11 is adapted to snugly engage this gasket.

In view of the fact that the valve 13 is normally held off of its seat by gravity, it can be seen that when the engine is idle and there is little or no steam pressure entering the cock "C" that any water of condensation entering the cock casing will flow past the valve and the seats 11 and 12. However, upon the admittance of steam, the pressure thereof will move the valve 13 on the seat 12 and hence loss of steam through the automatic drain valve is prevented.

The valve seats 11 and 12 are firmly held in position in a novel manner, as now will be described.

A bonnet 18 is utilized for this purpose and the inner end of the bonnet snugly receives the reduced end 19 of the outer valve seat 12. Ears 20 can be formed on the bonnet and stud screws 21 can be passed through these ears and threaded into the casing. Obviously, this will effectively hold the valve seats in position and permit the quick removal of the valve seats when necessary.

The bonnet 18 has formed directly therein a cylinder 22 and slidably mounted in this cylinder is an air-operated piston 23. Formed on or carried by the inner end of the piston is a plunger rod 24, and the bonnet is provided internally

with an axial guide sleeve 25 for this plunger. A suitable packing 26 can be placed in the guide sleeve to prevent the passage of air under pressure from the cylinder 22 into the cock casing. A spring 26 is employed for normally urging the piston away from the inner end of the cylinder and the plunger 24 away from the ball valve 13. The outer end of the cylinder 22 is closed by a cap 27, and this cap has connected therewith an air conduit pipe 28. The flow of air through the pipe 28 and into the cylinder 22 is controlled by the engineer, and in case the valve 13 sticks on its seat 12 then pressure can be admitted to the cylinder so that the piston 23 will move the plunger 24 into forcible engagement with the valve. This will also effectively permit the draining of the cylinder and the cock by the engineer when necessary or desirable.

By referring to Figure 1, it can be seen that the bonnet 18 is provided with a laterally extending drain outlet port 29 which communicates with the valve cock casing, and hence when the ball valve 13 is unseated, flow of fluid out of the casing is permitted.

It is to be also noted at this point that the valve 13 can be moved on its seat 11 by the plunger 24 when the engineer desires, for any reason, to shut off the flow of fluid through the cock casing.

Referring back to the relief valve 15, it will be noted that the same includes a valve head 30 and a stem 31. This stem is provided with radially extending guide ribs 32 which slidably engage the inner surface of the sleeve carried by the valve seat 14. Not only do these ribs form an effective guide for the relief valve, but also permit the flow of fluid past the stem.

The relief valve is normally held on its seat 14 by a relatively heavy expansion coil spring 33. The inner end of the spring engages a rock disc 34 having a rounded nose 35 fitted in a socket 36 formed in the outer face of the relief valve. The outer end of the spring 33 engages a yoke 37. This yoke has extending therethrough headed stud screws 38 which are threaded into the valve casing. Obviously, by tightening or loosening the stud screws, the tension of the spring can be increased or decreased. The tension of this spring is such as to normally hold the relief valve 15 on its seat under normal working steam conditions. However, when excess pressure is developed from any cause, which is liable to cause injury to the cylinder heads, such excess pressure will overcome the tension of the spring 33 and allow the unseating of the valve.

The strainer plug 9, as is clearly shown in Figure 2, includes a cylindrical perforated body 39, and this body has formed on one end thereof an externally threaded head 40 for engagement with the internally threaded bore of the cock casing or body 5. This head can be provided with a socket for the reception of a suitable turning wrench. The perforated cylindrical body extends into the cock casing 5 and terminates directly below the inlet side of the casing. This strainer plug is located directly between the ball drain valve 13 and the relief valve 15, and hence fluid flowing into the casing will of necessity pass

through the strainer plug, and this plug will effectively catch debris from the cylinder and protect the seats both for the ball drain valve 13 and the relief valve 15. I lay great stress on the location and arrangement of the strainer plug in that the single plug functions to protect all of the valve seats and is admirably seated to permit the convenient removal thereof from the casing.

From the foregoing description, it can be seen that I have provided an automatic cylinder drain cock of exceptionally simple and durable construction, and one which can be maintained in good working condition at all times.

Changes in details may be made without departing from the spirit or the scope of this invention, but what I claim as new is:

1. In an automatic cylinder drain cock, in combination, a casing having a connection to a cylinder and an outlet to atmosphere, said casing being open at one end, a pair of abutting valve seat members removably supported in said casing between said outlet and said connection and inserted in said casing through said open end and closing said open end, the outermost of said valve seats projecting beyond the casing, a bonnet engaging the projecting portion of the outermost of said valve seat members, fastening members securing said bonnet to said casing in tight contact with said outermost valve seat member, a valve body arranged between said valve seat members, said bonnet being provided with a cylinder, a piston in said cylinder, a plunger rod carried by the piston for engaging the valve body, spring means normally holding the piston and plunger away from the valve body and an inlet connection for the cylinder for permitting the entrance of fluid under pressure into said cylinder.

2. In an automatic cylinder cock of the type having a drain valve and a relief valve, a casing having a central chamber located between the drain valve and the relief valve, said chamber being open at its top and bottom, said open top constituting an inlet for connection with a cylinder, and a removable strainer plug detachably fitted in and closing the open bottom and having its upper end terminating at said inlet, whereby fluid entering said inlet to the drain and relief valves will pass through said strainer plug.

DANIEL ALLCOTT KELLY.
